(57) **CLAIM**

I claim the ornamental design for a closure, as shown and described.

DESCRIPTION

FIG. 1 is a perspective view from above of an alternative aspect of my container, namely a closure;

FIG. 2 is a front elevational view thereof;

FIG. 3 is a rear elevational view thereof;

FIG. 4 is a side elevational view from the left side;

FIG. 5 is an elevational view from the right side;

FIG. 6 is a top plan view; and,

FIG. 7 is a bottom plan view thereof.

The broken lines in the drawings illustrate the portions of the closure that form no part of the claimed design.
